January 13, 1945, Serial No. 117,401

Term of patent 14 years

(Cl. D14—6)

To all whom it may concern:

Be it known that I, Harold E. Dice, a citizen of the United States, residing at Canton, in the county of Stark and State of Ohio, have invented a new, original, and ornamental Design for a Display Plate for Automobiles, of which the following is a specification, reference being made to the accompanying drawing, forming part thereof.

Figure 1 is a front elevational view of a display plate for automobiles showing my new design.

Figure 2 is a plan view of the plate.

The characteristic features of my design reside in the portions shown in full lines.

This application was originally filed February 27, 1942, with the Serial Number D-106,014.

I claim:

The ornamental design for a display plate for automobiles, as shown and described.

HAROLD E. DICE.
